LENS GRINDING UNIT

Arthur F. Williams, St. Paul, Minn.

Application July 24, 1945, Serial No. 606,835

2 Claims. (Cl. 51—102)

1

This invention relates to a lens grinding unit which is adapted to support the optical lens which is to be ground with a marginal groove along the upper edge of the lens so that the lens may fit into the sectional frame of a spectacle to support the lens without making holes through the same. The unit includes a clamping arm which clamps the lens under spring tension to hold it firmly while it is marginally ground by the unit on the upper edge of the front surface thereof. The unit also includes a grinding wheel which is operated by any source of power and which is provided with a top shield that may be elevated away from the grinding wheel and there is also a lower shield having a channel for admitting water to the grinding wheel to keep the same moist while the wheel is in grinding operation.

The grinding unit also includes a truing device which is equipped with a piece of carbon set in an adjustable screw. The truing device includes a supporting shaft positioned above the shaft which drives the grinding wheel and having a hand engaging lever which permits the truing carbon to be moved across the face of the wheel to the surface of the grinding wheel.

The lens grinding unit also includes a spring clasp with an extended arm shaped for curvature to adapt itself to the standardized front arc groove cut in the optical lens. An auxiliary spiral spring is provided near the rear of the three layer spring to increase the tension of the spring clasp. This insures the proper guide for the lens as it is being grooved on the rear upper edge, the front arc groove being cut first.

The lens grinding unit includes a right angular shaft mounted in the base of the grinding unit support. This shaft is provided with a key-way slot for holding the shaft in line and in which a set screw may engage to lock the shaft in a set position. This right angular shaft may be adjusted by a knurled hand operating nut threaded to one end of the shaft which bears against the standard which supports the shaft and by means of a coil spring between the standard and the shoulder formed on the shaft the right angular arm may be moved in the desired direction. When it has been positioned as desired, the set screw will lock it in place. This right angular shaft supports the spring clip guide and also the guide plate which is formed with an arcuated surface fitting closely to the grinding surface of the grinding wheel and which is formed with a lens bearing surface which is arcuated to virtually the same arc as that of the upper edge of the lens to be ground. Thus when it is desired to grind

5 2

the toric lens with a marginal groove along its upper outer edge, the lens is held by the clamping arm and this is swung into position to be ground by the wheel with the top surface of the lens resting against the outer curved surface of the lens guiding plate. The right angular arm is adapted to support the lens guide plate and the spring clip guide in proper position or relation to the grinding wheel. The adjustment of the right angular arm regulates the depth of the marginal groove cut in the margin of the lens.

10 The optical lens grinding unit includes a supporting base having an upwardly extending standard which is formed with an integral head portion in which the drive shaft for the driving wheels is mounted and the shaft for the truing device is also mounted. The truing device shaft is positioned directly above and slightly to the rear of the longitudinal center of the shaft which drives the grinding wheel. The base member is formed with an integral forwardly projecting arm which forms a base support for the optical lens clamping arm.

15 The lens grinding unit includes a lens clamping arm mounted on a universal joint which is supported on a bracket arm projecting horizontally from the inner end of an adjustable shaft which is supported by the arm projecting from the main base portion of the unit. This shaft which supports the universal joint is provided with a longitudinal key-way and a rack and pinion operating means with a hand wheel for operating the rack and pinion so as to move the shaft supporting universal joint toward or away from the grinding 20 wheel. This movement carries the lens supporting clamping arm into the desired position in relation to the grinding wheel so that when the lens is supported in the lens clamping arm it may be swung into engagement with the edge of the grinding wheel to cut a marginal groove in the top edge of the lens.

25 The first groove in the spectacle lens is ground on the upper outer marginal edge of the same while the lens is held firmly in the lens clamping arm which forms the convex groove in the marginal edge of the lens. While the first groove is being ground with the lens held by the clamping arm the spring clip guide is moved away from the lens guide plate and the grinding wheel to permit the lens supporting arm to swing freely along the lens guide plate and against the grinding wheel.

30 After the first groove is formed in the lens it is released from the clamping arm by compressing the lever at the inner end of the same and then

55

the operator holds the lens by hand using the spring clip as a guide following in the first marginal groove in the lens and then the operator moves the lens past the grinding wheel to grind the second marginal groove on the opposite side of the lens to the first groove.

The lens clamping arm includes a lens clamp on the inner end of the arm with a coil spring for automatically closing the clamp. At the outer end of the lens clamping arm is provided a hand lever which operates an internal plunger in the shaft of the clamping arm to force the lens clamping plates into open position against the coil spring which normally holds them closed. Then by means of a universal joint the lens clamping arm is permitted to move with freedom of movement in a prescribed arc. I also provide an annular sleeve with a spring which provides a necessary frictional tension to hold the clamping arm against to free transverse rotation.

The free end of the lens clamping arm is provided with lens gripping pads; one is stationary and the other is annular to fit the contour of the lens.

These features together with details and other objects will be more clearly hereinafter set forth.

In the drawings forming part of the specification:

Figure 1 is a planned view of my lens grinding unit.

Figure 2 is a side elevation of my lens grinding unit looking toward the outer end of the shaft which supports the grinding wheel.

Figure 3 is the rear view of my optical lens grinding unit.

Figure 4 is a detail of the lens guiding plate positioned adjacent to the grinding wheel.

Figure 5 is also a detail of the lens guiding plate looking toward the front of the same.

Figure 6 is an end view looking toward the universally mounted end clamping plate of the lens clamping arm.

Figure 7 is a section on the line 7-7 of Figure 6.

Figure 8 is a perspective of a detail portion of a spectacle frame section used for supporting lenses grooved by my lens grinding unit.

Figure 9 is a cross section through the frame section shown in Figure 8 and illustrating the lens in section held in the spectacle frame.

Figure 10 is a cross section of a detail portion of an optical lens illustrating marginal grooves formed on either side of the top edge of the lens.

Figure 11 is a longitudinal sectional view through the unit B.

Figure 12 is an enlarged section on the line 12-12 of Figure 11.

Figure 13 is a view partially in section showing a lens held in contact with the grinding wheel for cutting the groove on the outside surface thereof with the guide shoe in inoperative position.

Figure 14 is an enlarged detailed sectional view of a portion of Figure 13.

Figure 15 is a view similar to Figure 14 showing the lens in position for grinding the groove on the outer or concave surface of the lens with the guide shoe in operative position.

Figure 16 is an enlarged perspective view of a portion of the machine showing the lens in position for grinding the groove on the front or convex surface of the upper edge of a lens.

Figure 17 is a view similar to Figure 16 showing the grooving of the rear or concave surface

of the lens on the upper edge, the lens being held by the operator against the lens guide and grinding wheel.

The lens grinding unit A is formed with a base member 10 adapted to be mounted on any suitable bed to hold the unit A firm for operation. The base member 10 extends upwardly in a conical form as illustrated in Figure 3 and is formed with an integral head portion 11 in which the drive shaft 12 is mounted. The head portion 11 forms a long bearing for the shaft 12 and I provide a coupling 13 which may be connected to any source of power such as an electric motor or other driving means to rotate the shaft 12. On the opposite end of the shaft 12 to the coupling 13 I mount a grinding wheel 14 which is held on the shaft by nut 15 so that the grinding wheel may be replaced when desired by a new wheel.

The wheel 14 is guarded over the top by the hinged guard 16 which may be lifted to expose the top of the grinding wheel 14 when desired. A lower guard and water channel 17 extends around from the back and over the lower portion of the grinding wheel as illustrated in Figure 2. This guard 17 has a water inlet opening 18 at the back of the same and a water outlet opening 19 is formed at the bottom of the guard 17 and is supported by the arm 20 to the shelf 21 which projects upwardly from the head 11 as illustrated in Figures 1 and 3.

The grinding wheel truing means is slideably mounted on the shaft 22 in the head 11 and is provided with a hand engaging lever 23, illustrated in Figure 1 to permit the shaft 22 to be freely moved in the bearings 24 formed in the head 11.

On one end of the shaft 22 I mount a threaded screw 25 which is formed with an operating head 26. The shaft 22 is bifurcated, being formed with a slot 27 so as to provide a tension against the threads of the screw 25 to hold the screw in set position. In the lower end of the screw 25, I mount a hard carbon member 28 which is for the purpose of truing the outer surface of the grinding wheel 14 when it is desired.

The truing operation of the wheel 14 is carried out by raising the guard 16 and then adjusting the screw 25 by the knurled knob 26 into the desired engagement with the surface of the wheel 14 and then while the grinding wheel is in rotary operation the lever 23 operates the shaft 22 to move the carbon cutter 28 across the surface of the wheel 14. In this manner the surface of the wheel 14 may be directed to insure a sharper cutting edge on the grinding wheel for cutting the marginal groove in the top edge of the optical lens as will later be set forth.

Normally the truing device is moved into a retarded position away from the wheel 14 and the guard 16 extends over the top of the grinding wheel 14. The free end 16' of the guard 16 is adapted to rest upon the top of the lens guiding plate 29 as illustrated in Figures 1 and 2.

The lens guiding plate 29 is supported by the front plate 30 which in turn is supported on the vertical shaft 31. The lower end of the shaft 31 is mounted in the bracket 32. The bracket 32 is supported by the right angular shaft 33 which extends through the bearing 34 formed on the back of the conical standard 10. The shaft 33 is formed with a longitudinal key-way 35 into which the set screw 36 engages to hold the shaft 33 in a horizontal position with the base 75 10. When set screw 36 is fully withdrawn from

keyway 35, bracket 32 and shaft 31 in Figure 2 may be moved in the direction of the dotted lines so that guide plate 29 may be moved away from grinding wheel 14.

A collar 37 is mounted on the shaft 33 and is held against movement in one direction by the pin 38 which extends through the shaft 33. A coil spring 39 is mounted around the shaft 33 and extends between the collar 37 and the shoulder 40 on the standard 10. One end of the shaft 33 is threaded and by means of the threaded nut 41 the shaft 33 may be adjusted to vary the position of the shaft in its mounting 34. The coil spring 39 moves the shaft in one direction when the set screw 36 is released and the threaded nut 41 operates to move the shaft against the action of the spring 39.

The shaft 33 is moved in a manner to properly adjust the lens guiding plate 29 so as to position the plate 29 in a predetermined position in relation to the surface of the grinding wheel 14. In this manner the lens guiding plate 29 may be positioned to vary the depth of the cut along the marginal edge of the optical lens.

The lens guide plate 29 is formed with a concave lens guiding surface 42. It is against this surface that the top edge of the lens rests while a marginal groove is formed by the cutter wheel 14 as the lens is moved over the concave guiding surface 42.

The lens guiding plate 29 is formed with a concaved surface 43 which fits closely to the surface of the grinding wheel 14 and in fact is concaved with the same outer periphery of the grinding wheel 14.

The front plate 30 supports the lens guiding spring 44, the shank of which is made up of several spring layers. A coil spring 45 is mounted on the front plate 30 as illustrated in Figure 1 and is adapted to bear against the leaves of the spring 44 to increase the tension of the spring 44 when it is desired by operating the nut 46 on the end of the shaft which supports the coil spring 45.

The spring 45 is formed with a lens guide shoe 47 illustrated in Figures 1, 4, and 5, to adjust the free end of the spring 44 I provide a cam 48 which may be operated by the hand lever 49 to bear against the inner surface of the leaves of the spring 44 to move the shoe 47 away from the grinding edge of the grinder 14 when the upper inner marginal groove is cut in a lens. The cam 48 is shown in Figures 4 and 5 and by means of the shoulder 50 formed on the back of the cam 48 and the adjustable screw 51 which is operated by the head 52, the normal position of the cam 48 may be adjusted. By means of this adjustment in the operation of the head 52, the cam 48 may be set against the inner surface of the guiding spring 44 to move the lens guiding shoe 47 toward or away from the grinding edge of the grinder 14. However, if it is desired to quickly move the shoe 47 away from the grinding surface of the wheel 14, the hand lever 49 may operate the cam 48 to move the shoe away from the grinding wheel 14 when the lever 49 is released the shoe 47 will return to the normal position bearing against the surface of the cam 48.

The lens guiding shoe 47 provides a guide against which the surface of the lens may rest while the top edge is resting against the lens guiding plate 29. Further the shoe 47 provides a guide for engaging in the marginal groove formed in the outer surface of the optical lens

when the lens is held by the hand of the operator and the final marginal groove is formed in the rear upper marginal edge of the lens. The engaging surface of the shoe 47 is curved to fit the convex outer surface of a lens.

In other words the optical lens is adapted to be grooved on both sides marginally on the top edge of the lens. The first groove in the marginal edge of the lens is formed by supporting the lens in the lens clamping lever B, the details of which will be more fully hereinafter set forth.

After the lens has been grooved on one side it can be removed from the clamp B and held by the hand of the operator and a marginal groove may be formed on the other side of the lens by holding the first groove in the lens against the guide shoe 47 and the top edge of the lens against the surface of the lens guiding plate 29 as illustrated in Figures 17 and 15.

The lens clamping lever is made up of a hollow shaft 53 in which the plunger 54 is operated to move the lens clamping arm 55 against the action of the coil spring 56 to move the lens gripping pad 57 away from the lens gripping pad 53. A knurled collar 59 adjusts the tension of the spring 56, the knurled collar being threaded on the outer surface of the shaft 53 adjacent to lens gripping pad 58.

The lens gripping pad 58 is freely mounted with a swivel joint 60 as illustrated in Figure 7 and Figure 11 to permit the pad 58 to adjust itself to the surface of the lens between the pads 57 and 58.

The arm 56 is operated by the plunger 54 which in turn is operated by the hand lever 61 which is mounted in the bracket 62 and fixed on the shaft 53 as illustrated in Figure 2.

The shaft 53 with the lens gripping pads 57 and 58 rotates in the bearing 63. A coil spring 64 mounted on the shaft 53 and operating against a fibre washer 65 which bears against the bearing 63 and against the collar 66 provides the desired tension or friction between the shaft 53 and the bearing 63 to prevent free rotation of the same.

The collar 66 can be set to regulate the tension of the spring 64. Thus I provide a frictional bearing which holds the shaft 53 to free rotation yet permits the shaft to be rotated so that the lens gripped between pads may be rotated as the lens is being ground by the wheel 14 and then bears against the guide plate 29.

The bearings 63 are mounted in a universal joint 67 which in turn is carried by the arm 68 mounted on the front end of the shaft 69. The universal joint 67 gives free movement to the shaft 53 and the end of the same which carries the lens gripping pads 57 and 58.

The shaft 69 is mounted in the bearing 70. The bearing 70 is supported by the upright standard 71 which in turn is mounted on the base arm 72 which is formed integral with the base 10 as illustrated in Figures 1 and 2.

The shaft 69 is formed with a longitudinal key-slot 73 in the top of the same and the shaft is held against rotation by a key fitting into the slot which key is held by the nuts 74 as illustrated in Figure 1.

On the bottom surface of the shaft 69 a longitudinal rack formed with gear teeth is formed which is adapted to mesh with a pinion (the pinion and rack not being illustrated in the drawings) and the pinion being operated by the shaft 75 which in turn is rotated by the hand wheel 76, thus by means of the wheel 76 the shaft 69 can be moved back and forth in the bearings 70

which in turn moves the arm 68 to carry the shaft 53 back and forth toward or away from the grinding wheel 14. The wheel 76 is operated to adjust the end of the shaft 53 which carries the lens between the pads 57 and 58 into the proper position in relation to the grinding wheel 14 so that the lens may be formed with a marginal groove by coming in contact with the grinding wheel 14.

The plate 81 directly below the universal joint 67 limits the swinging movement of the shaft 53 about the joint.

The frame section 81 is adapted to engage in the groove 78 of the lens 80. My lens grinding unit A is adapted to grind the groove 78 in the marginal edges of the lens, it will therefore be apparent that with my lens grinding unit A a marginal groove may be ground into both sides of the lens or into either side so that the lens may be slipped into a channel shaped frame section as illustrated in the enlarged detail illustrated in Figures 8 and 9.

I claim:

1. A lens groover including a base, a grinding wheel supported thereon, a guide plate having a curved surface opposed to and following the outer periphery of said grinding wheel for a short arc and another surface intersecting said curved surface and adapted to engage a lens edge, a lens guiding shoe positioned on the lens engaging surface of said guide plate and presenting a concave curved surface opposed to the peripheral surface of the grinding wheel and against which the lens is pressed by the pressure of the wheel against the lens, and spring means for retaining said lens guiding shoe against a lens positioned against said guide plate for grooving by said wheel.

2. A lens groover including a base, a grinding

5
10
15

wheel supported thereon, a guide plate having a curved surface opposed to and following the outer periphery of said grinding wheel for a short arc and another surface intersecting said curved surface and adapted to engage a lens edge, upper and lower guard means for said grinding wheel, said upper guard means being hinged to move away from the surface of the grinding wheel, said upper and lower guard means and said guide plate substantially encircling said grinding wheel, a lens guiding shoe positioned on the lens engaging surface of said guide plate and presenting a concave curved surface opposed to the peripheral surface of the grinding wheel and against which the lens is pressed by the pressure of the wheel against the lens, and spring means for retaining said lens guiding shoe against a lens positioned against said guide plate for grooving by said wheel.

ARTHUR F. WILLIAMS.
